BERNARD JOSEPH MOORE, OF STOKE-ON-TRENT, AND ARTHUR JOHN CAMPBELL, OF STONE, ENGLAND, ASSIGNORS OF ONE-HALF TO GIBBONS BROTHERS LIMITED, OF DUDLEY, ENGLAND, A COMPANY OF GREAT BRITAIN

ELECTRICALLY-HEATED KILN

Application filed November 26, 1927. Serial No. 235,930.

This invention relates to electrically heated kilns and is particularly applicable to electrically heated kilns of the tunnel type wherein trucks containing goods are passed successively through an entrance zone, a pre-heating zone, a heating zone, and a cooling zone.

One of the objects of the present invention is to provide improved means for supporting the heating coils in such manner that the danger of short circuiting due to expansion of the coils is avoided.

A further object of the present invention is to provide an improved arrangement of heating elements to obtain more uniform heating in the tunnel.

Referring to the drawings:—

Figure 1 is a sectional view on line 1—1 of Figure 2 of the pre-heating or heating sections of a tunnel.

Figure 2 is a sectional plan view.

Figure 3 is a transverse section on line 3—3.

Figure 4 is a view upon an enlarged scale showing the heating coils.

Figure 5 is a transverse section taken through two of the heating coils.

In the construction illustrated the kiln consists of a tunnel 1 built up of heat resisting blocks or bricks and having rails 2 at its base whereon trucks may run.

Between the heating chamber 3 of the tunnel and the rails and the chamber 4 in which the under carriage of the trucks run is a constricted opening 5 formed by projecting ridges 6 of the brick work.

The heating coils 7 of resistance wire or material are hung upon knife edge rods 8 of insulating material, the coils 7 being so large in relation to the rods 8 that they touch the rods only along their top edges.

By this arrangement it is possible to work at high temperatures and as such temperatures cause expansion and distortion of the coils 7 about midway along the length of each coil and below the coil a peg 9 of insulating material is secured in the adjacent wall 10 of the kiln.

The purpose of the pegs 9 is to prevent the coils 7 upon expansion or distortion or break-

age of the rods 8 from extending downwardly and forming contact with the coil beneath.

The rods 8 are supported at their ends by resting upon projections 11 from the wall 10 of the kiln.

When at high temperature the coils may expand to such a degree that those parts thereof which are adjacent to the wall 10 may come into contact with the wall. Since there can be no further movement in this direction or downwardly owing to the pegs 9 further expansion of the coils must take place in an outward direction. In order to prevent the coils from thus sliding the rods 8 laterally off the projections 11 the projections are provided with upwardly extending lips or flanges 12.

The leading in cables 13 pass into the kiln through suitable openings extending through the walls of the kiln from the outside.

In kilns of the type to which this invention relates difficulty has been experienced owing to the fact that the heated air in the kiln rises to the top so that the upper levels of the kiln become much hotter than its lower part.

In order to overcome this difficulty we provide in the pre-heating section 14 two rows 15 of heating elements which are disposed near the base of the hot chamber.

These rows of heating elements exceed the heating elements 16 of the heating section proper in length and comprise two thirds of the number of coils in the heating section.

One or more outlets such as 17 may be provided for the escape of the heated air and such outlets may be controlled by a valve or damper if desired.

What we claim then is:—

An electrically heated kiln comprising a tunnel, said tunnel having recesses in its walls, projections upon the walls of said tunnel within said recesses arranged in rows one above another, horizontal knife edged insulating rods carried by said projections and arranged one above another in spaced relationship, tension free coils of resistance wire wound around the insulating rods, lips upon the projections for retaining the insulating rods in position thereon, and pegs projecting from the walls of the furnace beneath each

resistance coil normally spaced therefrom to prevent an upper coil contacting with a coil immediately below in the event of the insulating rod carrying the upper coil breaking or the coil itself sagging.

5 In witness whereof we affix our signatures.

BERNARD JOSEPH MOORE.
ARTHUR JOHN CAMPBELL.
